WATER WHEEL BUCKET

Joseph J. Ring, Wauwatosa, Wis., assignor to
Allis-Chalmers Manufacturing Company, Mil-
waukee, Wis., a corporation of Delaware

Application May 21, 1934, Serial No. 726,699

4 Claims. (Cl. 253—114)

This invention relates to improvements in the construction of buckets for hydraulic turbines of the impulse type and more particularly to buckets which are built up from several elements 5 rather than formed as an integral structure.

Heretofore the buckets of impulse hydraulic turbines were formed as single units by processes such as casting by which the ellipsoids forming the bucket itself and the means for attaching the bucket to the rotor disc were formed at the same time. Such integral construction however required a separate pattern for each type and size of bucket and each bucket had to be separately cast. After casting, the buckets had to 10 be annealed to relieve casting stresses and each bucket then had to be separately finished. Such finishing required that the bucket be balanced and also finished to obtain uniform weight distribution in each bucket to avoid unbalance 15 stresses acting either centrifugally or laterally. It is readily apparent to even those not skilled in the art, that the above process is uneconomic and must result both in lack of uniformity of the product and in high cost.

It is therefore among the objects of the present invention to provide a bucket construction for impulse hydraulic turbines in which the bucket is assembled from a plurality of separably formed elements rather than formed as an integral structure.

Another object of the invention is to provide a bucket construction for impulse hydraulic turbines in which a bucket is built up from a plurality of elements which are each interchangeable 35 with similar elements.

Another object of the invention is to provide a bucket for impulse hydraulic turbines in which the bucket is built up from a plurality of elements which are in substantially finished condition thus 40 avoiding extended finishing operations on the irregular outline structure formed by the bucket.

Another object of the invention is to provide a bucket construction for hydraulic turbines of the impulse type in which the bucket is built up 45 from a plurality of elements which can be separately replaced to avoid scrapping the entire bucket upon wearing out of one portion thereof.

Objects and advantages other than those above 50 set forth will be apparent from the following description when read in connection with the accompanying drawing, in which:

Fig. 1 is a plan view looking downwardly on an impulse wheel bucket built up from a plurality 55 of separate elements;

Fig. 2 is a side elevational view of the structure illustrated in Fig. 1; and

Fig. 3 is a cross-sectional view taken on the plane III—III of Fig. 2 to illustrate the arrangement of the elements receiving and retaining the ellipsoids forming the jet receiving portion of the bucket and to illustrate the manner in which the receiving and retaining portions are interconnected.

Referring more particularly to the drawing by characters of reference, the reference numerals 5 and 6 designate adjacent ellipsoids which are preferably forged or stamped from a single piece of sheet material such as boiler plate and which form the jet receiving portion of a bucket construction for a hydraulic turbine of the impulse type. Due to the construction of the ellipsoids from sheet material, it may be difficult to secure a properly shaped jet divider or splitter at the intersection of the surfaces of the ellipsoids. If 10 a sharpened and extended splitter is required, a 15 separate knife shaped member 7 is suitably secured in the ellipsoids as shown in section in Fig. 3.

The ellipsoids are set into and retained within 20 a retaining structure or holder which may be termed a reinforcement, preferably formed from 25 separate elements. The major elements of the holder are plates 8 and 9 which are cut out to receive the ellipsoids. The plates 8 and 9 extend 30 about the ellipsoids in a direction substantially parallel with the greater axis thereof and extend rearwardly from the ellipsoids to provide means for engaging the rotor disc (not shown) 35 to which the plates are to be secured by suitable means employing the apertures formed therein. The plates 8, 9 are spaced by a bracing member 11 extending from the outer convex surface of the ellipsoids, at approximately the midpoint 40 thereof, downwardly and rearwardly between 45 and in contact with the plates. The plates 8, 9 and the brace 11 are joined by suitable means such as welding, bolting or riveting. The forward edge of the plates and the portions thereof adjacent the rear portion of the ellipsoids are 50 joined by substantially semi-circular straps 12 and 13 to which the ellipsoids are attached by suitable means. The upper edge portions of the ellipsoids between the plates 8, 9 are secured to a plate 14 which is suitably attached to the 55 plates 8, 9 and extends therebetween. The semi-circular straps 12, 13 are further stiffened by arc shaped straps 16 and 17 which extend from approximately the center section of the straps 12, 13 about the ellipsoids and extend into con- 55

tact with the plates 8, 9 to which they are attached. The several elements of the holder are thus formed and joined in such manner as to form a basket-like structure into which the ellipsoids are set and in which such ellipsoids are retained.

From the above it will be apparent that the several elements of the bucket are separately formed from plates or sheet material which is commercially manufactured to close limits and in highly finished form. The probabilities of deviation of weight in any number of the several elements are accordingly very slight thus eliminating the necessity for finishing of the completed structure to remain within predetermined weight limits. The several portions are produced in quantities by machine and are already in highly finished condition and require only such finishing as may be desired from the view point of appearance. Any one of the portions may be removed from a completed structure and be replaced without damage to the other portions thereof thus greatly reducing maintenance cost. The ellipsoids are firmly retained in the holder which is stayed and braced by the reinforcement, in every direction in which forces act thereon. The ellipsoids themselves therefore need be made only heavy enough to withstand corrosion and erosion because the forces tending to deform them are taken up by the various elements of the holder. Such elements are sufficiently uniform in shape to render calculation of the strength thereof relatively simple.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. A built up bucket for hydraulic turbines of the impulse type comprising jet receiving ellipsoids, and a reinforcement, for said ellipsoids, and comprising members respectively engaging a substantial portion of the edges of said ellipsoids, and extending transversely of and engaging the bottoms of said ellipsoids. 5

2. A built up bucket for hydraulic turbines of the impulse type comprising a plurality of joined jet receiving bowls of substantially ellipsoidal form, and a holder for said bowls forming a reinforcement comprising members extending around the periphery of said bowls from one end of the jet entering portion thereof to the other end of the jet entering portion thereof and members respectively extending along the convex surface and longitudinally of said bowls from the jet entering edge of the bucket to and beyond the opposite edge thereof to serve as lugs for attaching the buckets. 10 15 20

3. A built up bucket for hydraulic turbines of the impulse type comprising a plurality of joined jet receiving bowls of substantially ellipsoidal form, and a reinforcement comprising a member extending around the periphery of said bowls from one end of the jet entering portion thereof to the other end of the jet entering portion thereof. 25 30

4. A built up bucket for hydraulic turbines of the impulse type comprising a plurality of joined jet receiving bowls of substantially ellipsoidal form, and a reinforcement comprising members respectively extending along the convex surface and longitudinally of said bowls, transversely of said bowls, and around the periphery of each of said bowls from one end of the jet entering portion thereof to the opposite end of the jet entering portion thereof. 35 40
